United States Patent

Des. 237,773
Patented Nov. 25, 1975

237,773

LABORATORY STAND CLAMP OR LIKE ARTICLE

Arthur F. Johnson, Northbrook, Ill., assignor to
Humboldt Manufacturing Company, Norridge, Ill.

Filed Oct. 26, 1973, Ser. No. 409,928

Term of patent 14 years

Int. Cl. D24—02

U.S. Cl. D8—72

Fig. 1.

Fig. 2.

Fig. 3.

Fig. 4.

FIG. 1 is a perspective view of a laboratory stand clamp or like article showing my new design;

FIG. 2 is a top plan view of FIG. 1 as seen from above;

FIG. 3 is an elevation as seen from the rear of FIG. 1; and

FIG. 4 is an endwise elevation of the same.

I claim:

The ornamental design for a laboratory stand clamp or like article, as shown.
